CURL CLIP

Pearl Eicher, near North Canton, Ohio

Application August 17, 1939, Serial No. 290,655

9 Claims. (Cl. 132—31)

The invention relates to the general type of curl clips including opposed lever arms pivoted with respect to each other and spring urged towards each other for gripping the moistened hair strands of a curl and holding the curl in position on the head until dry.

In usual curl clips of this general type the gripping arms extend substantially at right angles to the axis of the curl, which is usually a ringlet, one of the gripping arms extending beneath the curl and resting upon the head, and the other gripping arm extending across the outside of the curl and covering a substantial portion of the same.

Such a usual curl clip does not hold the curl as securely as is desirable, does not make a curl as perfect as desirable, and delays the drying of the curl.

The objects of the present invention include the provision of an improved curl clip which is adapted to hold a curl securely in position on the head, which is adapted to make curls more perfect than is ordinarily attainable by the usual ordinary curl clips or hair pins, and which is adapted for permitting quicker drying of a curl than is attainable by the use of a usual curl clip having spring urged gripping arms pivoted with respect to each other, the gripping arms of which extend at substantially right angles to the plane of the curl and one of the gripping arms extending beneath the curl and lying against the head and the other gripping arm extending across and covering a substantial portion of the curl.

Further objects of the present invention include the provision of an improved curl clip which is adapted for rapid and easy application to the moistened hair strands of a curl.

Further objects of the present invention include the provision of an improved curl clip of simplified construction and which is adapted for easy and economical production.

The foregoing and other objects are attained by the curl clip, parts, combinations, and sub-combinations of the present invention, the nature of which is set forth in the following general statement, and by way of example preferred embodiments of which and their mode of operation are set forth in the following description, and which are particularly and distinctly pointed out and set forth in the appended claims forming part hereof.

The nature of the improved curl clip of the present invention may be stated in general terms as including levers pivoted with respect to each other and having opposed spring pressed gripping

arms for gripping the hair strands at one side of a curl or ringlet and a hook foot extending from the outer end of one of the gripping arms, the hook foot being angled with respect to the gripping arm from which it extends and extending beyond the outer surface of one of the arms preferably across and beyond the outer end of the other arm and being adapted to hook under the curl and rest against the head and maintain the clip clear of the curl beyond the gripped hair strands.

By way of example, preferred embodiments of the improved curl clip and parts thereof, are illustrated in the accompanying drawing forming part hereof, in which

Figure 1 is an enlarged side elevation of a preferred embodiment of the improved curl clip hereof;

Fig. 2, a top plan view thereof;

Fig. 3, an isometric view thereof; and

Fig. 4, an enlarged fragmentary perspective view of the side of a woman's head showing the improved curl clip gripping a hair curl or ringlet.

Similar numerals refer to similar parts throughout the several views.

The illustrated preferred embodiment of the improved curl clip hereof is indicated generally by 10 and includes opposed spring pressed pivoted levers indicated generally by 11 and 12, each preferably formed from sheet metal and pivoted with respect to each other as by means of tongues 13 extending from opposite sides and intermediate the ends of the lever 11, the tongues 13 overlapping tongues 14 extending from opposite sides and intermediate the ends of the lever 12.

The overlapping tongues 13 and 14 have registering apertures formed therein through which a pivot pin 15 extends and is secured, and the longitudinal axis 16 of the pivot pin 15 is the pivoting axis of the clip.

At one side of the pivoting axis 16 of the clip, the lever 11 includes a curl gripping arm 17, and at the same side of the pivoting axis 16, the lever 12 includes a curl gripping arm 18 opposed to the curl gripping arm 17.

From the outer end of the curl gripping arm 17 a hook foot 19 extends at an angle to the arm 17 beyond the outer surface of one of the arms and preferably across and beyond the outer end of the curl gripping arm 18.

At the other side of the pivoting axis 16, the lever 11 includes a manipulating arm 20 angled with respect to the hair gripping arm 17, and at the same side of the pivoting axis 16, the lever 12 includes a manipulating arm 21 angled 55

with respect to the hair gripping arm 18 and opposite the manipulating arm 20 of the lever 11.

5 The hair gripping arms or members 17 and 18 are spring urged towards each other as by a coil spring 22 wound about the pivot pin 15 and having its ends 23 and 24 respectively pressing against the opposed inner faces of the manipulating arms 20 and 21 respectively.

10 The hair gripping arms 17 and 18 are preferably slightly concave towards each other radially of the pivoting axis 16, as best shown in Fig. 1, and the arms 17 and 18 also preferably have formed therein elongated central apertures 25 and 26 respectively.

15 18 The hair gripping arms 17 and 18 are preferably laterally tapered with their widest portions adjacent the pivoting axis 16, and the hook foot 19 is likewise preferably similarly tapered to minimize the area of the hair gripping portions 20 of the clip.

In using the improved curl clip 10, moistened strands of hair are formed into a curl or ringlet 27 as shown in Fig. 4, as by winding around the finger of the operator. The gripping arms 17 and 18 of the clip 10 are then opened by pressing on the manipulating arms 20 and 21, and the hair strands at one side of the curl 27 are engaged by the gripping arms 17 and 18, with the angled hook foot 19 extending beneath the curl and laying against the head, and maintaining the gripping arms of the clip 10 clear of the curl beyond the gripped hair strands.

The curl 27 is thus quickly secured by the improved clip 10, with only a small area of the curl obstructed by the clip, so that rapid drying and setting of the curl is effected.

The embodiments of the present improvements illustrated and described herein are by way of example, and the scope of the present invention is not limited to the same or to the particular details thereof, but is commensurate with any and all novel subject matter contained herein which at any time properly under the patent laws may be set forth in the claims hereof or 45 originating herein, and the elements of any such claims are intended to include their functional or structural equivalents.

I claim:

50 1. A curl clip for securing moistened hair strands of a hair ringlet in position on the head of a person until dry, including opposed gripping arms movably associated with each other, means urging the gripping arms towards each other for gripping therebetween the hair strands at one 55 side of the ringlet, and a hook foot extending from an outer end of one of the gripping arms at an angle thereto and beyond the outer surface of one of the arms, the hook foot being adapted to hook under the ringlet and rest against the head and maintain the clip clear of the ringlet beyond the gripped hair strands.

55 2. A curl clip including opposed hair strand

gripping arms, means movably connecting the arms for pivoting with respect to each other, means urging the gripping arms towards each other, and a hook foot extending from an outer end of one of the gripping arms at an angle thereto and beyond the outer surface of one of the arms. 5

3. A curl clip including opposed hair strand gripping arms, means movably connecting the arms for pivoting with respect to each other, 10 means urging the gripping arms towards each other, and a hook foot extending from an outer end of one of the gripping arms at an angle thereto and across and beyond the outer end of the other gripping arm. 15

4. A curl clip including opposed hair strand gripping arms, means movably connecting the arms for pivoting with respect to each other, spring means urging the gripping arms towards each other, and a hook foot extending from an outer end of one of the gripping arms at an angle thereto and beyond the outer surface of one of the arms. 20

5. A curl clip including opposed hair strand gripping arms, means movably connecting the 25 arms for pivoting with respect to each other, spring means urging the gripping arms towards each other, and a hook foot extending from an outer end of one of the gripping arms at an angle thereto and across and beyond the outer end of the other gripping arm. 30

6. A curl clip including opposed hair strand gripping arms, means movably connecting the arms and urging the arms towards each other, and a hook foot extending from an outer end 35 of one of the gripping arms at an angle thereto and beyond the outer surface of one of the arms.

7. A curl clip including opposed hair strand gripping arms, means movably connecting the arms and urging the arms towards each other, 40 and a hook foot extending from an outer end of one of the gripping arms at an angle thereto and across and beyond the outer end of the other gripping arm.

8. A curl clip including opposed hair strand 45 gripping arms, means movably connecting the arms and urging the arms towards each other, and a hook foot extending from an outer end of one of the gripping arms at an angle thereto and beyond the outer surface of one of the arms, 50 the gripping arms being longitudinally concaved towards each other.

9. A curl clip including opposed hair strand gripping arms, means movably connecting the arms and urging the arms towards each other, 55 and a hook foot extending from an outer end of one of the gripping arms at an angle thereto and across and beyond the outer end of the other gripping arm, the gripping arms being longitudinally concaved towards each other. 60
